APPARATUS FOR DISCHARGING COMPACT MATTER FROM SHAFT FURNACES

Otto Hubmann, Bad Homburg, Germany

Application December 13, 1949, Serial No. 132,774
In Switzerland January 20, 1949

5 Claims. (Cl. 48—87)

1

The invention relates to an apparatus for discharging compact matter from shaft-furnaces. Shaft furnaces as, for example, gas producers for the gasification of solid fuels, are frequently fitted with a rotary grate and a water bowl. By means of the rotation of the grate the material to be removed, as for example, the residues of gasifications, is discharged from the furnace via a water lock closing the furnace to the atmosphere.

For shaft furnaces operating with higher pressures as, for example, several atmospheres, this kind of discharging is unsuitable. In place of a water lock discharge sluices are used and the whole weight of the charge column rests on a table with a central opening. By means of a rotary grate or the like situated above this central opening the residues as, for example, ashes of a gasified solid fuel, are removed through the central opening toward the discharging sluice. It has been found, however, that, for example, with the gasification of solid fuel by means of oxygen or oxygen-enriched air and steam under a pressure of several atmospheres, the moving parts of this discharging device are easily destroyed or deformed by overheating or corroding attacks when coming in contact with the gasifying means or the incandescent material. This may happen even with the use of expensive highly heat-resisting construction materials.

The object of the present invention is to overcome these drawbacks by installing water-cooling in the discharge parts of the gas-producers or similar shaft furnaces in which, for example, dioxide of sulphur is reduced by contact with incandescent fuels in such a way that the movable parts of the rotary grate as well as its bearings, which are situated in the interior of the furnace, are cooled by water. The invention can be used with particular advantage with furnaces operating under higher pressures as, for instance, several atmospheres, or in cases where oxygen and/or steam at higher temperatures come to reaction therein.

The water-cooling, according to the invention, may, for example, be carried out in such a way that a rotary hood situated above the central opening of the table supporting the charge, is mounted on a fixed hollow shaft inside of the shaft-furnace. Through the hollow shaft the hood is supplied with cooling-water, which also efficiently cools the bearings of the hood and allows their being arranged at a place where the forces acting on the hood can be borne without additional moments of flexure.

2

According to the invention the hood is provided with a water chamber from which water is fed to all parts of the hood including the particularly exposed shoes. In spite of the high temperatures prevailing in such a shaft-furnace as, for example, in a gas-producer or the like, and the presence of oxygen or other corroding gases it now becomes possible to attach an annular spur gear directly to the hood, since this gear can also be water-cooled without difficulty. In this way the discharge of the waste material as, for instance, the residues of reaction, is facilitated considerably, since a central receiving chamber may be provided immediately below the hood, especially if, according to the invention, the hollow shaft, on which the hood is mounted, is supported by two or more arms connecting it with the shell of the gas producer.

In order to avoid the use of packings and stuffing-boxes for the cooling-water inside of the gas-producer it is advantageous to operate the rotary hood as a steam producer which preferably communicates with the gasification chamber in order to have the same pressure in the water chamber of the hood as in the gasification chamber, thus making it possible for the developed steam to flow out, for example, into the shaft-furnace. In this way the apparatus according to the invention can be operated with a pressure of 20 atmospheres or more, without running the risk of additionally stressing the cooling chambers by pressure differences. The water level in the hood can easily be controlled by arranging outside of the gas-producer and communicating with the water chamber of the hood a water container provided with simple float-valves for keeping the water at the desired level.

With an apparatus according to the invention the temperature of the hood remains always below the dewpoint of the gases in the furnace, so that even with conditions favorable to corrosion there is no danger of chemical attacks on the construction material as, for instance, by acids, such as sulphur dioxide, sulphur trioxide or the like.

Since, according to the invention, a large receiving chamber is provided beneath the rotary grate for receiving the waste material to be discharged from the furnace, it becomes possible to improve the discharging itself considerably by providing centrally below the hollow shaft of the hood a valve-like discharging device for the residues, by means of which these residues can be transferred from the receiving chamber to a

sluicing chamber of normal design below it. The water-cooled hollow shaft provides a favorable opportunity for installing a hydraulic drive for operating the discharging device for removing the residues or the like, since the water-cooling according to the invention efficiently protects all the equipment necessary for this purpose against excessively high temperatures. The invention also makes it possible to considerably decrease the height of the whole furnace plant and thereby bring about a corresponding saving in construction material.

With some shaft furnaces, as, for example, those for the gasification of solid fuels by means of oxygen or oxygen-enriched air and superheated steam or the like under pressure, it is desirable to avoid a cooling-down of the gasifying medium by contact with the water-cooled surfaces of the gas producer and the hood by introducing the gasification means as directly as possible into the fuel-bed. This can be achieved, according to the invention, by leading a fixed feed-line, lined with insulating material, centrally through the fixed hollow shaft and the hood, so that no bearings or packings are required in connection with the rotary hood.

In some particular cases as, for instance, for the production of gases rich in hydrogen by the gasification of coal with oxygen and steam or the like, it is possible by means of the apparatus according to the invention to feed gasifying medium of several different compositions through the hollow shaft into the fuel-bed as, for example, mixtures of oxygen and steam with varying concentrations of oxygen or even methane-containing gases for the purpose of cracking the methane to carbon-dioxide and hydrogen. In this case several feed lines may appropriately be led through the shell of the gas producer and the hollow shaft, which preferably open into the fuel-bed at different heights. This can be achieved, for instance, by suitably shaping the central top part of the rotary hood and providing it for this purpose with several entrance openings at different heights. The different gasifying medium may be continuously or periodically introduced through these openings.

An apparatus according to the invention is shown in Figs. 1 and 2 by way of example. Fig. 1 is a cross-section of the lower part of a gas-producer in which coal is continuously gasified by means of oxygen and steam superheated to 500° C. under pressure of several atmospheres. At the right hand half of Fig. 1 is shown a cross-section of a discharging-shoe of the hood while at the left hand side is shown a cross-section of the hood body itself. Fig. 2 shows a plan view of the hood with the central cover 12 of the water chamber removed.

1 is the double-walled water-cooled shell of the gas-producer. The column of solid fuels rests on the annular plate 2, the central opening of which is covered by the rotary hood 3. The latter is mounted in bearings on the fixed shaft 4. At the bottom the gas-producer is closed by the conical funnel 5, preferably fitted with an insulating lining 21. The hollow shaft 4 is connected with this funnel by means of arms 6. The annular spur-gear 7 is fastened to hood 3 by means of hollow ribs 11 and is driven from the outside by pinion 8 and shaft 9 in the usual manner. Hood 3 contains the water-chamber 10, which communicates through hollow ribs 11 with the water-chamber 18 of the annular spur gear 7. The water-chamber 10

of the rotary hood which, for example, is filled with water up to the level indicated by the line 22, is protected by the double plate 12 against the column of fuels in such a way that the steam 5 developing in the water-chamber is allowed to escape into the fuel-bed. In case gases of different composition are to be introduced separately through different lines this plate 12 may be substituted by a dome-shaped top-piece with 10 openings at several steps, so that, for example, the different feed-lines led through the hollow shaft may each be connected to a different step. The rotary hood 3 is expediently fitted with discharging shoes 13 for removing the residues of 15 gasification during the rotation of the hood into the interior of the hood and the receiving chamber situated below it. The water-chamber 10 of the hood 3 communicates, according to the embodiment of the invention shown in Figs. 1 20 and 2, via the hollow space in the shaft 4 and the arms 6 with the feed-line 14, which also connects the water-chamber 10 with a container (not shown) placed at the same height as this chamber and arranged outside the gas-producer. 25 The water-level of the container can be adjusted in a well-known way by means of a float-controlled valve.

It is not absolutely necessary that the hollow shaft 4 be filled with water. The water-cooling 30 of the hood 3 and the hollow arms 6 already effects a sufficient cooling of the bearings. The feeding of the cooling water to the water-chamber 10 of the hood may be done by a special feed-line which expediently can be led through 35 one of the supporting arms of the hollow shaft and the hollow shaft itself. In this case the hollow shaft is extended so far upward that the water cannot run out of the hood and flow into it.

40 For discharging the gasification residues from the gas-producer a conical valve 15 is fitted below the hollow shaft 4, which periodically establishes a connection between the chamber 19 and the sluicing device of usual design below it. For operating the valve 15 a controlling cylinder 16 is provided, which in the well-known way 45 may be actuated by water, oil or steam under pressure.

Through one of the arms 6 and the hollow shaft 4 the interiorly insulated line 17 is led so far upward that it ends just below the plate 12 in order to allow a direct feeding of the gasification means into the fuel-bed.

The apparatus according to the invention also 55 allows the operation of shaft furnaces in cases where highly heated gases are introduced and even when these gases contain heavily corroding constituents or when the shaft furnace has to be operated under pressure of several atmospheres. At the same time a considerable saving 60 of construction material, especially of heat-resisting metals, is effected. For the gasification of fuels it becomes possible to operate with fuels rich in ashes and tending toward slag-formation with a relatively low consumption of steam.

What I claim is:

1. In an apparatus for discharging material from a shaft furnace, a stationary furnace charge 70 supporting member provided with a central opening, a perpendicular hollow shaft spaced from the inner edge of said supporting member held in the furnace below said supporting member by at least two hollow supporting arms adapted to have water introduced therein, a covering

member above said supporting member mounted for rotation upon a bearing on said perpendicular hollow shaft and extending over the space between said hollow shaft and the stationary supporting member, said covering member comprising a casing containing a water chamber, means for supplying water to said chamber, said covering member also comprising means for urging the lower portion of the furnace charge toward the annular space between the hollow shaft and the inner edge of the stationary supporting member.

2. An apparatus in accordance with claim 1, comprising means for supplying water to said water chamber through said hollow shaft.

3. An apparatus in accordance with claim 1, in which said covering member is provided with an opening in communication with the interior of said hollow shaft and in which at least one conduit is provided in said hollow shaft for feeding gas to the shaft furnace through said opening in the covering member.

4. An apparatus in accordance with claim 1, comprising in addition means affixed to the covering member for the rotating thereof, and com-

prising also an annular spur gear provided with a water chamber communicating with the water chamber in said covering member.

5. An apparatus in accordance with claim 1, in which said casing is provided with at least one opening communicating between the water chamber and the interior of the furnace whereby steam formed in said water chamber is directly fed to the furnace charge through said opening.
